DESIGN FOR A BOOKMARK

Edward Rabbin and Frank Drucker, New York,
N. Y.

Application August 2, 1938, Serial No. 79,021

Term of patent 3½ years

To all whom it may concern:

Be it known that we, Edward Rabbin and Frank Drucker, citizens of the United States and residents of the city of New York, in the county of Kings and State of New York, have invented a new, original, and ornamental Design for a Bookmark, of which the following is a specification, reference being had to the accompanying drawing, constituting a part thereof.

Fig. 1 is a plan view of a bookmark showing our new design.

Fig. 2 is a side view of same.

We claim:

The ornamental design for a bookmark substantially as shown.

EDWARD RABBIN.
FRANK DRUCKER.
